(57) **CLAIM**

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the first image in a sequence for a display screen with animated graphical user interface showing a second embodiment thereof;

FIG. 8 is the second image thereof;

FIG. 9 is the third image thereof;

FIG. 10 is the fourth image thereof;

FIG. 11 is the fifth image thereof;

FIG. 12 is the sixth image thereof;

FIG. 13 is the seventh image thereof;

FIG. 14 is the first image in a sequence for a display screen with animated graphical user interface showing a third embodiment thereof;

FIG. 15 is the second image thereof;

FIG. 16 is the third image thereof;

FIG. 17 is the fourth image thereof;

FIG. 18 is the fifth image thereof; and,

FIG. 19 is the sixth image thereof.

The appearance of the animated graphical user interface sequentially transitions between the images shown in FIGS. 1-6, 7-13, and 14-19. The process or period in which one image transitions to another forms no part of the claimed design. The broken-line showing of the text, display screen, and the remainder of the graphical user interface illustrate portions of the display screen with animated graphical user interface and forms no part of the claimed design.
